UNITED STATES PATENT OFFICE.

CHARLES GORDON, OF CHELSEA, MASSACHUSETTS.

HAMMOCK-CANOPY.

1,138,210.

Specification of Letters Patent.

Patented May 4, 1915.

Application filed June 15, 1910. Serial No. 566,899.

To all whom it may concern:

Be it known that I, CHARLES GORDON, a citizen of the United States, and resident of Chelsea, county of Suffolk, and State of Massachusetts, have invented an Improvement in Hammock-Canopies, of which the following description, in connection with the accompanying drawing, is a specification, like characters on the drawing representing like parts.

This invention relates to a canopy for couch hammocks which have recently come into widespread use, and its object is to provide a canopy of netting which can be readily attached to and suspended over the hammock in such a manner as to protect the user from flies, mosquitoes, and other annoyances.

The invention presents a device for this purpose and of this character which is simple and strong in construction and which permits ready access to the hammock.

The nature of the invention will appear from the accompanying description and drawings and will be particularly pointed out in the claim.

The drawings illustrate a couch hammock of the ordinary type with a canopy of this invention attached thereto.

In the drawings, Figure 1 is a perspective view of a couch hammock with the canopy of this invention in place; Fig. 2 is a detail in vertical cross section of a portion of the end of a hammock and the canopy; Fig. 3 is a detail showing the method of attachment of the cloth and netting portions of the canopy.

A couch hammock of the ordinary type is illustrated and need not be described in detail. It comprises the usual frame 1, mattress 2, side strips 3, ends 4, supporting cords 5, and suspending rings 6.

The canopy is made up of two end portions, formed preferably of closely woven cloth, and a body portion of netting or mesh goods. The end portions are shown at 7 and are preferably of the same width as the hammock and extend upwardly preferably to the supporting rings 6. As shown, these end portions slope at the top to correspond with the contour of the exterior supporting cords.

The netting 8 is united to the side edges and top of the end portions 7, as indicated in Fig. 3, the edge of the cloth end portion 7 being inturned at 9 over the edge of the

netting 8 and stitched thereto to form a welt, thus protecting and strengthening the edge of the netting.

The lower side edges of the end portions 7 are not united to the netting and there are thus left flaps 10 at either side of the body portion of netting, and flaps 11 at the bottom of each end portion. The flaps 10 of the netting are bound with binding, as 12, indicated at 12.

At suitable intervals the body portion of the netting is braced by longitudinally-extending tapes 13 stitched to the netting and extending into the welt at the edge of the 70 end portions. Suitable fastening devices are supplied at the ends of the tapes and are herein shown as grommets 14, passing through the welt and tape, and cords 15 by which connection is made to the grommets 75 or suspending rings of the hammock proper.

The tapes 13 thus take all strain off the netting and enable the body portion of the canopy to be drawn up taut and connected firmly to the ends of the hammock, thus supporting it effectively in position over the 80 hammock.

The flaps 12 of the netting and 11 of the end portions enable the canopy to be fitted readily around the bottom of the hammock. 85 The flaps 12 of the netting hang down outside where they are not liable to be injured and torn by the user of the hammock, while the flaps 11 of the end portions may lie over the mattress 2 and beneath any pillow 90 which may be used, or may be tucked under the mattress itself. In Fig. 2 they are shown as resting on the top of the mattress.

The canopy thus provided with this invention presents a structure of great 95 strength, one which is readily constructed and which effectively protects the user, and which can be readily attached and detached from the hammock.

Having fully described my invention what 100 I claim as new and desire to secure by Letters Patent is:

As a new article of manufacture a couch hammock canopy comprising cloth end portions, a netting top and side portions, the end 105 portions along their top and upper part of their side edges being inturned and united to the netting top and upper part of the netting side portions respectively, and forming a welt, the lower part of the edges of the 110 netting side portions and the cloth end portions being free and disconnected whereby

- flaps are left at the bottoms of both of the end and side portions extending the entire length of the side portions and to the lower edge of the frame of the hammock, tapes
5 stitched longitudinally of the canopy at the juncture of the top and side portions and at the juncture of the two top portions, and at the juncture of the end and side portions and extending into the welts at said points,
10 tapes stitched around the free edges of the netting flap portions and fastening devices connected to the juncture of the tapes and

welts, said tapes thereby taking strain off the netting and enabling the canopy to be drawn taut and connected firmly to the ends 15 of the hammock.

In testimony whereof, I have signed my name to this specification, in the presence of two subscribing witnesses.

CHARLES GORDON.
